WASTE AND OVERFLOW FITTING

Application filed February 29, 1932. Serial No. 595,705.

This invention relates to an improved waste-and-overflow fitting, and particularly to fittings of the type referred to for use in connection with bathtubs, though not so limited.

One of the main objects of my present invention is to provide a waste-and-overflow fitting of superior neatness, combined with ease and convenience of operation.

- 10 A further object of my invention is to provide a fitting of the character referred to, in which the operating-mechanism for the waste-control valve may be readily and conveniently adjusted.
- 15 With the above and other objects in view, as will appear from the following, my invention consists in a waste-and-overflow fitting of the type referred to, having certain features of construction and combinations 20 and arrangements of parts as will be herein-after described and particularly recited in the claims.

In the accompanying drawings:

Fig. 1 is a broken face view of the overflow-portion of my improved fitting, shown as applied to a bathtub, which latter is broken away;

Fig. 2 is a broken view in vertical central section, showing the complete fitting applied 30 to a bathtub, which latter is broken away;

Fig. 3 is a broken, detail, sectional view taken on the line 3-3 of Fig. 2;

Fig. 4 is a transverse sectional view taken on the line 4-4 of Fig. 2;

Fig. 5 is a face view of the overflow-head, detached; and

Fig. 6 is a perspective view of the unit comprising the face-plate, operating-member, and associated parts, detached.

- 40 The particular waste-and-overflow fitting herein chosen for the illustration of my invention comprises a cast-metal overflow-head 10 having the general form of an elbow, and provided in its lower end with a socket 45 11, into which the upper end of an overflow-tube 12 is adapted to be soldered or otherwise secured. The forward face of the head 10 is recessed to provide an annular gasket-seat 13, into which is seated a ring-like gasket 14, 50 adapted to be compressed between the said

seat and the outer surface of the wall 15 of a bathtub.

The head 10 is provided adjacent the gasket-seat 13 with a pair of inwardly-extending lugs 16-16, respectively projecting 55 into the L-shaped hollow interior 17 of the said head, and each formed with a threaded perforation 18 for the reception of binding-screws as will hereinafter appear.

Located against the inner face of the wall 60 15 of the bathtub, axially in line with the open forward face of the overflow-head 10, is a domical face-plate 19 provided on its rear face, adjacent its edge, with three (more or less) spacing-lugs 20 which serve to hold the 65 said face-plate in spaced relationship forwardly of the inner face of the bathtub-wall 15, so as to create a substantially-annular overflow-passage 21 therearound, which communicates with the L-shaped interior 17 of the said head 70 10, through a circular opening 22 in the bathtub-wall 15 and a corresponding opening 23 in the gasket 14.

The bathtub-wall 15 and the gasket 14 are clamped, so to speak, between the overflow-head 10 and the face-plate 19 so as to provide a watertight joint, by means of a pair of clamping-screws 24-24 passing rearwardly through the face-plate 19 on the respective 75 opposite sides of the center thereof, and into the threaded perforations 18 in the lugs 16-16 of the head 10. The perforations in the face-plate 19 through which the clamping screws 24-24 pass are the only perforations or breaks in smoothness of the exposed 80 surface of the face-plate. The heads of the clamping-screws 24-24 and the perforations are complementarily formed so that when the screws are in position the exposed surfaces of their heads and the exposed surface 85 of the face-plate form one substantially-smooth and unbroken surface easy to clean and neat in appearance.

The rear face of the face-plate 19 is provided with an axially-located rearwardly-extending boss 25 having a rearwardly-opening 90 threaded socket 26 receiving the threaded stem 27 of a screw-stud 28 upon which is mounted, with capacity for lateral oscillation, a waste valve-operating member, gener- 100

ally designated by the numeral 29. The said operating-member 29 is provided at its forward end with a relatively-slender lever-arm 30 extending radially outward through the upper portion of the overflow-passage 21, and adapted to swing laterally between the two uppermost of the spacing-lugs 20, which latter also acts as stops for the said lever-arm. The lever-arm just referred to is provided at its outer end with a forwardly-extending finger-piece 31 to afford a convenient grip for the manipulation of a waste-valve, as will hereinafter appear.

The rear end of the operating-member 29 above referred to is provided with a radially-offsetting arm 32 mounting, in its outer end, a rearwardly-extending stud 33 over which the perforated upper end of a coupling-head 34 is slipped and retained in place on the said stud by means of a cotter-pin 35 or other suitable means.

The coupling-head 34 just above referred to is formed with an axially-arranged downwardly opening threaded bore 36 receiving the threaded upper end of a screw-eye 37, the eye 38 of which is connected, by means of a pair of links 39 and 40, to a bridge-plate 41 formed integral with and extending diametrically across the upper end of a tubular waste-valve 42, open at its lower end as shown and open at its upper end save for the space occupied by the slender bridge-plate 41 thereat.

The said waste-valve 42 is adapted to reciprocate within a waste-valve-housing 43 and is provided on its lower outer edge with a conically-shaped seat 44, adapted to coact with a similarly-shaped seat 45 formed within the said housing 43 adjacent the lower end thereof.

The waste-valve 42 and its housing 43 may be of any approved type, but as herein shown, the said housing is of T-shaped form, having an upwardly-extending arm 46 receiving the lower end of the waste-tube 12, and having a lateral arm 47 connected to a horizontal tube 48 leading to the drainage-opening (not shown) of the bathtub. The lower arm 49 of the housing 43 is internally threaded as at 50 for being coupled to a drainpipe.

From the foregoing, it will be seen that the waste-valve 42 may be raised and lowered with reference to the seat 45 in its housing 43 by swinging the lever-arm 30 from side to side between the two upper spacing-lugs 20, and should the water-level in the bathtub rise unduly high, it may drain outwardly through the overflow-passage 21 and into the overflow-tube 12, and thence through the tubular waste-valve 42 for ultimate drainage through a suitable waste-pipe.

In the accompanying drawings, the waste-valve 42 is shown in its elevated position so as to permit the bathtub to drain outwardly through the waste-tube 48, and it will be

noted that when the said valve 42 is in its raised position, the stud 33 is located slightly past dead center, so that the weight of the valve 42 and its associated parts will hold the lever-arm 30 against the left-hand one of the two upper spacing-lugs 20, as viewed in Fig. 1, whereby the said valve, acting through its own weight and the weight of the associated parts, serves to retain itself in its raised position.

For the purpose of causing the lever-arm 30 to swing to one side or the other of a vertical position, to thus insure definite "off" and "on" positions for the waste-valve 42, the under face of the operating-member 29 is formed with a cylindrical recess 51 housing a helical spring 52, against which is seated a detent-plunger 53 projecting downwardly for yielding engagement with the upper surface of a cam-plate 54 extending rearwardly from the rear face of the face-plate 19 with which it may be formed integral if desired, or secured thereto by solder, brazing or otherwise, as shown.

By so arranging the parts that the lever-arm 30 or its equivalent operating-member extends radially outward from behind the face-plate 19, not only is a neat and attractive appearance obtained, but the absence of pivots, etc., on the front face of the said face-plate facilitates the maintaining of the exposed portion of the overflow-fitting in a clean and attractive condition.

Furthermore, by mounting the operating-member 29 on the removable face-plate 19, the screw-eye 37 may be readily adjusted to in turn adjust the position of the valve 42, by removing the clamping-screws 24 and drawing the face-plate 19 outward so as to bring the screw-eye 37 and the coupling-head 34 within reach for screwing the former upward or downward in the said coupling-head as may be required.

It will be understood by those skilled in the art that my invention may assume varied physical forms without departing from my inventive concept and I, therefore, do not limit myself to the specific embodiment herein chosen for illustration, but only as indicated in the appended claims.

I claim:

1. In a waste-and-overflow fitting, the combination with an overflow-head; of a face-plate having a substantially unbroken exposed front surface and spaced forwardly of the said overflow-head in position to receive a bathtub-wall therebetween, and provided with means to form an overflow-passage between the rim of the face-plate and the bathtub-wall; a waste-valve; and control-means for the said waste-valve including a finger-lever mounted upon the rear face of the said face-plate and projecting outwardly beyond the periphery thereof.
2. In a waste-and-overflow fitting, the

combination with an overflow-head; of a face-plate having a substantially unbroken exposed front surface and spaced forwardly of the said overflow-head in position to receive a bathtub-wall therebetween and formed upon its rim with spacing-lugs to provide a peripheral overflow-passage between the rim of the face-plate and the bathtub-wall; a waste-valve; and control-means for the said waste-valve, including a finger-lever mounted upon a projection formed upon the rear face of the said face-plate and projecting outwardly through the said peripheral overflow-passage.

3. In a waste-and-overflow fitting, the combination with an over-flow head; of a face-plate spaced forwardly of the said overflow-head in position to receive a bathtub-wall therebetween, and provided with spacing-lugs to hold it in spaced relationship to the bathtub-wall and to create between the latter and the said face-plate a peripheral overflow-passage; clamping-means coacting with the overflow-head and with the face-plate to hold the same together and formed to provide with the face-plate a substantially unbroken outer surface; a waste-valve; and control-means for the said waste-valve, including a finger-lever mounted behind the said face-plate and projecting outwardly through the said peripheral overflow-passage.

4. In a waste-and-overflow fitting, the combination with an overflow-head; of a face-plate spaced forwardly of the said overflow-head in position to receive a bathtub-wall therebetween, and provided with an overflow-passage; a waste-valve; control-means for the said waste-valve including a finger-lever mounted upon the rear face of the said face-plate and projecting outwardly beyond the periphery thereof; and detent-means also positioned upon the rear face of the face-plate for yieldingly holding the said finger-lever in its on and off positions respectively.

5. In a waste-and-overflow fitting, the combination with an overflow-head; of a face-plate spaced forwardly of the said overflow-head in position to receive a bathtub-wall therebetween, and provided with an overflow-passage; a waste-valve; control-means for the said waste-valve including a finger-lever mounted upon the rear face of the said face-plate and projecting outwardly beyond the periphery thereof; and detent-means for yieldingly holding the said finger-lever in its on and off positions respectively, including two interacting members, one of which is yielding, one of the said members being carried by the said finger-lever and the other being carried by the rear face of the said face-plate.

6. In a waste-and-overflow fitting, the combination with an overflow-head adapted

to be applied to the outer surface of a bathtub-wall; of a substantially imperforate face-plate adapted to be applied to the inner surface of a bathtub-wall and provided with spacing-means upon the rim of the said face-plate to afford a plurality of passages between the rim of the face-plate and the bathtub-wall, clamping-means to fasten the face-plate to the overflow-head and grip the bathtub-wall therebetween and adapted to fit into the face-plate to maintain the outer surface thereof substantially unbroken and smooth, and waste-valve operating-means mounted upon the rear face of the face-plate and provided with an actuating lever extending through and movable in one of the said passages.

In testimony whereof, I have signed this specification.
